United States Patent Office

Des. 194,222
Patented Dec. 11, 1962

194,222

COLLAPSIBLE TUBE

Charles A. Rolley, Reno, Nev., and Edward H. Southwell,
Los Angeles, Calif., assignors to Closure Specialty Company,
Los Angeles, Calif., co-partnership

Filed Mar. 22, 1961, Ser. No. 64,436

Term of patent 14 years

(Cl. D58—17)

Fig. 1.

Fig. 2.

Fig. 3.

Fig. 4.

FIG. 1 is a side elevational view of a collapsible tube showing our new design.

FIG. 2 is a side elevational view taken from the right side of FIG. 1.

FIG. 3 is a top plan view of the portion shown in solid lines in FIG. 1.

FIG. 4 is a bottom view of the portion shown in solid lines in FIG. 1.

The essential features of our design reside in the portions shown in full lines.

We claim:

The ornamental design for a collapsible tube, as shown and described.
